8 Claims. (Cl. 114—43.5)

(Granted under the act of March 3, 1883, as
amended April 30, 1928; 370 O. G. 757)

1

This invention relates to recovering seaplanes from the water and it has a particular relation to the recovery of a seaplane and hoisting it aboard a vessel while underway.

One of the objects of the present invention is the provision of apparatus for use in recovering a seaplane and taking it aboard ship while the ship is underway, by maneuvering the ship in such manner as to form a slick on the lee side thereof into which a seaplane may be landed, taxied to recovery position and towed alongside during the recovery operations.

Another object of the invention is the provision of a device adapted to be towed astern or alongside of a vessel and with which a taxiing seaplane engages to be towed thereby while the hoisting tackle is being connected with the plane.

Another object of the invention is the provision of a device of the character described which may be towed alongside a vessel, where it is more convenient in certain types of ships to hoist a plane on board, without danger of the device veering toward the side of the vessel and damaging the plane by collision therewith.

A further object of the invention is the provision of a recovery device which will smooth out turbulent water and form a slick for a seaplane taxiing toward the device.

With these and other objects in view, as well as other advantages that may be incident to the use of the improvements, the invention consists in the parts and combinations thereof hereinafter set forth and claimed, with the understanding that the several necessary elements constituting the same may be varied in proportion and arrangement without departing from the nature and scope of the invention, as defined in the appended claims.

In order to make the invention more clearly understood, there are shown in the accompanying drawings, means for carrying the invention into practical use, without limiting the improvements in their useful application to the particular construction, which, for the purpose of explanation, have been made the subject of illustration.

In the accompanying drawings:

Fig. 1 is a plan view of a seaplane recovering device constructed in accordance with the invention;

Fig. 2 is a side elevational view of the structure shown in Fig. 1;

Fig. 3 is a diagrammatic view looking aft, illustrating the manner in which the device is towed alongside of a vessel; and

2

Fig. 4 is a similar view looking toward the side of the vessel.

Referring to the drawings, and particularly to Figs. 1 and 2 thereof, a seaplane recovery device is shown as comprising a float or sled 10 having an upwardly curved forward edge 11 and a rod or bar 12 extending across its rear edge to which a rearwardly trailing net 13 is secured. This net is of a relatively wide mesh and is adapted to be engaged by a hook 14 on the pontoon 15 of a seaplane, indicated generally at 16. This hook may be pivoted so as to fold back in passing over the net or in the event the plane overrides the net and rides up onto the float or sled. A fabric apron 17, preferably canvas soaked in red lead is secured to the rear edge of the float 10 and extends rearwardly beneath the net 13 and is preferably laced to the outside strands thereof. This apron is shown as terminating at a point about one-half the length of the net but it may be of equal length or even longer if so desired, and tends to support the net and provide a slick for an approaching seaplane. Streamers 18 may be attached to the rear edge of the apron 17 and trail through the water while the device is being towed to maintain the net extended and to indicate its position to the pilot. A bridle 19 is secured to the underside of the float 10 adjacent to its forward edge for attachment to a tow line 20 leading from a boom 21 extending from the side of the vessel. The bottom side of the float 10 is provided with a pair of angularly disposed vanes or fins 22 for preventing the device from veering toward the side of the vessel and damaging the plane by contact therewith. The vanes 22 may correspond to either port or starboard rudder, according to which side of the ship the recovery is made. The vanes 22 tend to move the sled or float away from the vessel on the side of the slick and the sled is maintained under control and prevented from veering too far from the side of the vessel by a breast line 20'.

When it is desired to take a seaplane on board, the boom 21 is swung out, the sled 10 lowered into the water, the tow line 20 adjusted until the sled is opposite the crane and a breast line 20' adjusted until the sled is the proper distance from the side of the ship. At this time the ship steams on such course as necessary to put the wind broad on the bow of the side on which the sled is being towed. Upon signal the ship turns through 90° towards the side on which the sled is being towed, thereby creating a slick and also a lee by putting the wind on the opposite bow. The seaplane lands in the slick just before the turn is com-

pleted and taxies through the smooth water of the slick towards the sled. As the pontoon 15 rides up on the sled, the pilot closes his engine throttle, allowing the pontoon to settle and the hook 14 to engage the net. The plane is now towed along with the net where it is quite stable and is in position abreast the crane so that tackle 23 may be connected to hoisting bridle 24 and the plane lifted out of the water and placed on board the ship. The entire operation is performed while the ship is underway and while the plane is in the slick, formed by the turning of the ship, where the water is relatively smooth. If, for any reason, the pilot should desire to free the plane from the device, he merely speeds up the engine, which causes the pontoon 15 to rise and lift the hook 14 clear of the net.

The invention described herein may be manufactured and/or used by or for the Government of the United States of America for governmental purposes without the payment of any royalties thereon or therefor.

We claim:

1. Device for recovering seaplanes from the water comprising a float adapted to be towed by a vessel, a net secured to said float and extending aft therefrom for engagement by a hook on the pontoon of a seaplane and a fabric apron secured to the rear of said float and disposed beneath said net for supporting the same and providing a slick therefor and for an approaching seaplane.

2. Device for recovering seaplanes from the water comprising a float adapted to be towed by a vessel, a net secured to said float and extending aft therefrom for engagement by a hook on the pontoon of a seaplane, a fabric apron disposed beneath said net for supporting the same and providing a slick therefor and for an approaching seaplane, and means for controlling lateral movement of said device.

3. Device for recovering seaplanes from the water comprising a float adapted to be towed by a vessel, a net secured to said float and extending aft therefrom for engagement by a hook on the pontoon of a seaplane, a fabric apron disposed beneath said net for supporting the same and providing a slick therefor and for an approaching seaplane, and a vane on said float for controlling lateral movement of said device.

4. Device for recovering seaplanes from the water comprising a float adapted to be towed by a vessel, a net secured to said float and extending aft therefrom for engagement by a hook on the pontoon of a seaplane, a fabric apron disposed beneath said net for supporting the same and providing a slick therefor and for an approaching seaplane, and an angularly disposed vane on said float for preventing said device from veering toward the vessel when towed alongside thereof.

5. Device for recovering seaplanes from the water comprising a sled adapted to be towed by

a vessel, a net secured to said sled and extending aft therefrom for engagement by a hook on the pontoon of a seaplane and a fabric apron attached to the rear of said sled and disposed beneath said net for supporting the same and providing a slick therefor and for an approaching seaplane, the rear edge of said apron terminating along a line horizontally spaced in a fore and aft direction from the rear edge of said net.

10. 6. Device for recovering seaplanes from the water comprising a sled adapted to be towed by a vessel, a net secured to said sled and extending aft therefrom for engagement by a hook on the pontoon of a seaplane and a fabric apron attached to the rear of said sled and disposed beneath said net and terminating short of the rear end thereof for supporting the same and providing a slick therefor and for an approaching seaplane.

20. 7. Device for recovering seaplanes from the water comprising a sled adapted to be towed by a vessel, a net secured to said sled and extending aft therefrom for engagement by a hook on the pontoon of a seaplane, a fabric apron attached to the rear of said sled and disposed beneath said net for supporting the same and providing a slick therefor and for an approaching seaplane, and streamers attached to the rear of said apron and along the sides of said net for maintaining the net extended while being towed.

30. 8. Device for recovering seaplanes from the water comprising a float adapted to be towed by a vessel, a net secured to said float and extending aft therefrom for engagement by a hook on the pontoon of a seaplane and a fabric apron secured to the rear of said float and disposed beneath said net for supporting the same and providing a slick therefor and for an approaching seaplane.
